A. MERCER

FIRE SAFETY DEVICE FOR DWELLINGS AND FACTORIES

Filed May 19, 1927

INVENTOR
BY Alexander Mercer
Soltan Polachek
ATTORNEY

UNITED STATES PATENT OFFICE.

ALEXANDER MERCER, OF WAINFLEET, ONTARIO, CANADA.

FIRE SAFETY DEVICE FOR DWELLINGS AND FACTORIES.

Application filed May 19, 1927. Serial No. 192,605.

This invention relates generally to safety devices, and has more particular reference to a fire safety device for dwellings and factories.

5 The invention has for an object the provision of a fire safety device for dwellings and factories, or the like, which is reliable, accurate and efficient in action.

10 The invention has for a further object, the provision of a fire safety device for dwellings and factories, which can be manufactured and installed at a reasonable cost.

15 For further comprehension of the invention and of the objects and advantages thereof, reference will be had to the following description and accompanying drawing and to the appended claims in which the various novel features of the invention are more particularly set forth.

20 Referring to the accompanying drawing, forming a material part of this disclosure.

Fig. 1 is a schematic vertical sectional view of a house having the invention applied thereto, for clearness in illustrating, 25 certain wiring being omitted.

Fig. 2 is a view similar to Fig. 1, but showing only the wiring omitted in Fig. 1.

Fig. 3 is a vertical sectional view, taken on the line 3—3 of Fig. 2.

30 Fig. 4 is a horizontal sectional view, taken on the line 4—4 of Fig. 2.

Fig. 5 is a horizontal sectional view, taken on the line 5—5 of Fig. 1.

35 Fig. 6 is a fragmentary view of the house, with a modified form of the invention device applied thereto, and certain schematic wiring.

40 Fig. 7 is a vertical sectional view of the cartridge holder, taken on the line 7—7 of Fig. 4, and schematic wiring of the device being applied to this view.

Fig. 8 is an enlarged detail view of the 45 adjustable cartridge holder shown in Fig. 6.

The reference numeral 10 indicates a building, either residential or a factory, standing on the ground 11, having a water main 12 therebeneath. A connection 13 from the main 12, leads through one of the walls of house 10, and into the bottom of chamber 14 of a casing 15 having a projecting side wall 16. A plurality of small pipes 17 connect with the top of chamber 14 and lead separately to various portions of the house, being provided at intervals with sprinklers 18. The portions of the pipe 17 adjacent the top of the chamber 14, are each provided

with a valve having an operating stem 18' connected to the ends of a plurality of levers 19 hinged intermediate of their ends, as at 20, to the side wall 16 of the casing 15. 60

The free ends of the levers 19 extend over the cartridges 21 of a cartridge holder 22 supported on the exterior of the house 10. A plurality of pairs of wires 23 connect with separate mechanism, hereinafter described, 65 within the cartridge holder for individually discharging any one of the cartridges 21, when a fire fuse wire 24 separately associated with the wires 23 is burnt by fire. The wires 24 lead separately to various portions of the house 10. 70

75 The cartridge holder 22 has an interior chamber 35 accessible, by a removable block normally held in place by a screw 37. Each cartridge 21 has a trigger 38 pivotally supported to the holder 22, and forcibly urged towards said cartridge by a spring 39 also supported to the holder 22. An arm 40 pivotally secured to member 22, normally engages one end of the trigger 38 and holds 80 the trigger against engagement with the cartridge 21. A solenoid 41 is attached to the member 22, and upon being energized is capable of moving the free end of the arm 40 to free the trigger 38 and permit the 85 spring 39 to thrust the trigger against the cartridge and explode the same. The wires 23 electrically connect solenoid 41 in series with a battery 42, and a switch 43. A spring 44 is connected to normally close switch 43. 90

A normally energized solenoid 45 is connected to the switch and holds the switch open. This solenoid 45 is in series with the fuse wire 24 and a source of power wires 46. When the fuse wire 24 burns, the circuit of 95 solenoid 45 is broken, and the spring 44 closes the switch 43. Solenoid 41 now being in a complete circuit is energized, and moves the arm 40 to free the trigger 38. The spring 39 then throws the trigger against 100 the cartridge and explodes it.

105 When a cartridge 21 is discharged it makes sufficient noise to be heard quite some distance, calling attention to the fire in the house. The shot from the cartridge impinges against the end of the lever 19 which projects thereover, moving this end of the lever upwardly and moving the other end of the lever downwardly, thus moving stem 18', opening the valve, and water from the main 12 is permitted to flow to certain of the 110 sprinklers 18 acting to extinguish the fire.

An alarm 25 is attached to the house above the levers 19, and has a downwardly projecting arm 26 adapted to be pushed upwardly by any of the levers 19 to cause the alarm to start ringing until the arm is manually pulled downwardly again. The ringing alarm also gives notice of the fire.

In Fig. 6 a modification is disclosed showing the cartridge holder 22', hingedly mounted to the house, as at 28, and provided with a projecting screw 29 engaging in a slot 30 of an arcuate arm 31 secured to the house, the center of curvature of the arcuate arm 31, coinciding with the hinge 28. The levers 19 are of sufficient length to extend into the path of cartridge discharge in any position of the cartridge holder. If it is unsafe for the cartridges to fire vertically upward, screw 29 may be loosened and the cartridge body moved obliquely to a desirable position about the hinge 28, and thus locked by retightening the screw 29. The alarm 25 may be connected by supporting wires 32 to an indicator box 33 located in a fire apparatus station, so that as the alarm 25 operates, indication is given on the indicator box 33, notifying the fire department of the fire.

While I have described and illustrated the preferred form, construction, and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

Having thus described my invention what I claim as new and desire to secure by United States Letters Patent is:

1. A device of the class described, comprising a water supply, a casing with a chamber, the water supply being connected with the bottom of the casing, sprinkler connections to different parts of a building, and connected to the top of the chamber, valves operated by stems in these connections, and adjacent the top of the chamber, levers pivoted to the chamber and connected to the

stems, a cartridge holder with cartridges secured to the outside of the building, the free end of the levers projecting over the cartridges, fuse wires to different parts of the building, and means for exploding a cartridge individually as certain of the fuse wires burn, the shot from the cartridge moving the adjacent lever and causing certain sprinklers to operate.

2. A device of the class described, comprising a water supply, a casing with a chamber, the water supply being connected with the bottom of the casing, sprinkler connections to different parts of a building, and connected to the top of the chamber, valves operated by stems in these connections, and adjacent the top of the chamber, levers pivoted to the chamber and connected to the stems, a cartridge holder with cartridges adjustably secured to the outside of the building, the free end of the levers projecting over the cartridges, fuse wires to different parts of the building, and means for exploding a cartridge individually as certain of the fuse wires burn, the shot from the cartridge moving the adjacent lever, and causing certain sprinklers to operate an alarm operated by said moving lever.

3. In a device of the class described, the combination with the exterior wall of a building, a sprinkler system for said building and levers projecting from the building for turning on certain of the sprinklers, of a cartridge holder positioned beneath the levers, and hingedly connected to the exterior of the wall of the building, an arm provided with an elongated arcuate aperture also connected to said wall of the building, the center of curvature of the arcuate aperture coinciding with the hinge connection, and a screw from the cartridge holder, engaging in the elongated aperture, and means for fixing the position of said screw with respect to said aperture.

In testimony whereof I have affixed my signature.

ALEXANDER MERCER.
